UNITED STATES PATENT OFFICE.

WILLIAM L. MEUSCHKE, OF LINCOLN, MISSOURI.

CARRIAGE-RETURN MECHANISM FOR TYPEWRITERS.

1,396,865.

Specification of Letters Patent. Patented Nov. 15, 1921.

Application filed August 29, 1919. Serial No. 320,606.

To all whom it may concern:

Be it known that I, WILLIAM L. MEUSCHKE, a citizen of the United States, residing at Lincoln, in the county of Benton and State 5 of Missouri, have invented a new and useful Carriage-Return Mechanism for Typewriters, of which the following is a specification.

The present invention appertains generally to typewriters and aims to provide returning mechanism operable for automatically returning the typewriter carriage to starting position, to eliminate the laborious operation necessary with ordinary typewriters to return the carriage against the tension of the advancing spring thereof after each line has been typewritten.

It is the object of the invention to provide a return mechanism of the nature indicated, 20 which will by simply touching a key, result in the quick return of the carriage, thus saving time and labor.

Another object of the invention is to provide a mechanism of the nature indicated 25 which is comparatively simple and inexpensive in construction, which can be readily embodied in various styles of typewriters, and which will be thoroughly efficient and practical in use.

30 A still further object of the invention is the provision of novel means for automatically turning the platen the desired number of steps or spaces during the return of the carriage.

35 With the foregoing and other objects in view which will appear as the description proceeds, the invention resides in the combination and arrangement of parts and in the details of construction hereinafter described 40 and claimed, it being understood that changes in the precise embodiment of the invention herein disclosed, can be made within the scope of what is claimed, without departing from the spirit of the invention.

45 The invention is illustrated in the accompanying drawings, wherein:—

Figure 1 is a front view of a typewriter embodying the present improvements, portions being removed to simplify the illustration.

Fig. 2 is a rear view, with portions removed.

Fig. 3 is a longitudinal section from front to rear, portions being broken away.

55 In the drawings, the numeral 1 designates the frame of the typewriter, on which

the carriage 2 is movable, and the key levers are designated 3. Most of the working parts of the typewriter have not been shown, since they are old and well known.

In carrying out the invention, a rack 4 is pivotally connected, as at 5, with the carriage 2, and is movable into and out of engagement with a return gear 6 located at the right hand side of the frame or at any other suitable point. A gear 7 is mounted for rotation upon the stub shaft 8 upon which the gear 6 is also rotatable, said gears being relatively rotatable, and having a spiral or other suitable power storing spring 9 therebetween, one end of the spring being connected, as at 10, to the gear or returning wheel 6, the other end being connected, as at 11, with the gear 7. The gear 7 is rotated during the operation of the key levers, to wind up the spring 9 and store sufficient energy therein for returning the carriage when the line has been completed. The operative connection between the gear 7 and key levers 3 includes a shaft 12 journaled for rotation in suitable bearings 13 carried by the frame and having a pinion 14 meshing with the gear 7 and a bevel pinion 15 meshing with a bevel gear 16 rotatable with a spur gear 17, said gears 16 and 17 being mounted upon a suitable stub shaft 18 carried by the frame. A spur gear 19 meshes with the spur gear 17, said gears being preferably at the right hand side of the frame, and the gear 19 being mounted on a stub shaft 20. An oscillatory member 21 is mounted upon the shaft 20 and carries one or more pawls or dogs 22 for engaging a ratchet wheel 23 mounted upon the shaft 20. Said ratchet wheel 23 and gear 19 are secured to the shaft 20 to rotate in unison, while the member 21 is loose upon the shaft and has a segment 24 meshing with a segment 25 pivoted to the frame, as at 26. The segment 25 has an arm 27 to which is connected a hanger 28 which extends under the key levers 3, whereby when said levers are depressed during the operation of the typewriter, a hanger 28 will be reciprocated, said hanger being yieldably raised under the influence of a spring 28', which as illustrated, is connected to the arm 27 although it can be located at any other suitable point.

During the feeding or advance movement of the carriage, the rack 4 is lifted off of the gear 6, to enable the rack to be advanced with the carriage past said gear without inter-

ference, and for this purpose, a lifting lever 29 is pivoted, as at 30, to the frame and extends under a flange 30' with which the rack 4 is provided, said flange sliding on said lever. The lever is connected by a link 31 with a bell crank lever 32 pivoted to the lower portion of the frame, and in turn connected by a forwardly extending link 33 with a bell crank key lever 34 having the 10 key or finger piece 35 which can be touched or depressed by the operator when the line has been completed. When the key 35 is depressed, this will transmit motion to the lever 29 whereby it permits the rack 4 to drop into engagement with the gear 6, the key 35 being normally raised by a suitable spring 35' to raise the flange 30' and the rack 4 during the advance movement of the carriage.

15 20 When the rack 4 is raised out of engagement with the gear 6, said gear is locked against rotation by means of a dog 36 pivoted, as at 37, to the frame, and swung by a spring 38 into engagement with the gear 25 when released. A dog 36 is automatically disengaged from the gear 6 when the rack 4 drops into engagement with said gear, this being accomplished by the provision of an outstanding pin or lug 39 on the lever 29. 30 Thus, when the lever 29 is operated by the depression of the key 35, to permit the rack 4 to gravitate into engagement with the gear 6, the pin or lug 39 swings the dog 36 away from the gear 6.

35 The operation of the returning mechanism is as follows:—During the operation of the key levers 3, with the dog 36 in engagement with the gear 6, the hanger 28 will be reciprocated, whereby to oscillate the segment 25 40 which in turn oscillates the segment 24. The pawl and ratchet connection between the segment 24 and gear 19 will impart intermittent rotary movement to said gear, which motion is transmitted by the intervening 45 gears to the gear 7, thus winding up the spring 9, the reverse rotation of said gears being prevented by the pawl or dog 19' engaging the gear 19 or any other gear of the train. The spring 9 is thus wound up 50 during the advance movement of the carriage, and sufficient power is stored in said spring for returning the carriage against the tension of the carriage feeding or advancing spring (not shown) of ordinary 55 operation, as will be readily understood. During the winding up of the spring 9, the gear 6 cannot rotate since it is held by the dog or catch 36. When the line has been completed, the operator depresses the key 35, which lets the rack 4 move into engagement with the gear 6, and the dog 36 is 60 disengaged from the gear 6, thus releasing said gear, which will immediately be rotated by the spring 9 to move the rack 4 in the 65 direction to return the carriage to initial or starting position. Then when the carriage is returned, which consumes but a slight interval of time, the key 35 in being released results in the rack 4 being lifted from the gear 6, and the dog 36 being again 70 swung into engagement with said gear, for the next operation.

75 In order to turn the platen during the return movement of the carriage, and to accomplish said result automatically, there is provided a rack 41 mounted slidably in suitable bearings 40 carried by the carriage, preferably at the front of the carriage. A pinion 42 meshes with the rack 41 and is carried by a shaft 43 journaled in a suitable bearing 44. This shaft 43 is connected by arm and links or other suitable connection 45 with the platen advancing or rotating device 47 of ordinary construction and operation, and said device 47 in being returned by spring tension, will return the shaft 43, pinion 42 and rack 41 to normal position in the direction of advance movement of the carriage. A stop 48, such as commonly used, is pivoted or otherwise carried by the frame 1 to be engaged by an adjustable stop 49 carried by the carriage, to limit the return movement of the carriage so as to properly start the line. A stop 50 is mounted adjustably on the rack 41, in any 90 suitable manner, to engage the stop 48 before it is engaged by the stop 49 as the carriage is returned to starting position. It is preferable to provide a scale 51 adjacent to the rack 41 and containing a plurality of 95 longitudinally offset letter spacing graduations 52 with which a pointer 53 on the adjustable stop 50 co-operates. There is one series of graduations 52 for each spacing of the line, to facilitate the adjustment of the stop 50 with respect to the stop 49. Thus, when the stop 49 is adjusted to one position, and it is desired to single space the line, the stop 50 is set one space ahead of the stop 49, which can be readily done by the assistance 100 of the scale 51. If double spacing of the lines is desired, the stop 50 is set two graduations ahead of the stop 49 and if triple spacing is desired, the stop 50 is set three 105 graduations ahead of the stop 49. Consequently, when the stop 50 is set for single spacing, this will provide for the single spacing movement of the rack 41 relative to the carriage 2 when the carriage is returned. The stop 50 engages the stop 48 just one step or graduation ahead of the 110 stop 49, and the carriage 2 then has a slight movement before the stop 49 engages the stop 48, thus moving the rack 41 a single step relatively to the carriage, and rotating the pinion 42 and shaft 43 one step. This 115 will move the device 47 one step to advance the platen one step. However, if the stop 50 is set two steps or graduations ahead of the stop 49, it will contact with the stop 49 120

125 130

quicker, thus providing for a relatively larger movement of the rack 41 with respect to the carriage 2 before the stop 49 hits the stop 48. The pinion 42, shaft 43 and device 5 47 are therefore moved two steps, to advance the platen two steps, as in double spacing. It will therefore be noted that the farther the stop 50 is set ahead of the stop 49, the greater will be the advance movement of 10 the platen. When the carriage is advanced, the stop 49 is the first to move away from the stop 48, after which the stop 50 can move away from the stop 49 and permit the rack 41 to shift to the right, as seen in Fig. 15 1, when the platen advancing device 47 is returned to normal position.

Having thus described the invention, what is claimed as new is:—

1. The combination with a typewriter 20 having a carriage and operating means, of power storing means including a spring and a gear rotated thereby, an operative connection between said spring and operating means for winding up the spring, a rack 25 connected to the carriage and engageable with said gear, means for normally discon-

nnecting said rack and gear and to normally lock said gear, the last mentioned means being operable in part to permit engagement of the rack and gear and release the latter. 30

2. The combination with a typewriter having a carriage and operating means, of power storing means including a spring and a gear rotated thereby, an operative connection between said spring and operating 35 means to wind up the spring, a rack carried by the carriage and movable into and out of engagement with said gear, means for normally moving the rack out of engagement with said gear and operable in part to permit engagement of the rack with the gear, and means controlled by the last mentioned means for preventing the rotation of said gear when the rack is disconnected therefrom. 45

In testimony that I claim the foregoing as my own, I have hereto affixed my signature in the presence of two witnesses.

WILLIAM L. MEUSCHKE.
